Specification for Design.

Patented Jan. 18, 1921.

Application filed July 19, 1920. Serial No. 397,508. Term of patent 7 years.

To all whom it may concern:

Be it known that I, GEORGE F. PARKER, a citizen of the United States, residing at Newburyport, in the county of Essex and State of Massachusetts, have invented a new, original and ornamental Design for a Tray, Dish, Plate, Platter, Bowl, Compote, Basket, or Analogous Article of Hollow Ware, of which the following is a specification, reference being had to the accompanying drawing, forming a part thereof.

In the accompanying drawing Figure 1 is a plan view of my design shown embodied in a meat tray, and Fig. 2 is a section on the line 2—2 of Fig. 1.

The design comprises an ornamental design having the configuration and characteristics delineated and, as shown, is embodied in a meat tray, but it is contemplated that the design may, with suitable adaptation, also be embodied in, or applied to, dishes, plates, platters, bowls, compotes, baskets and other analogous articles of hollow ware.

I claim:

The ornamental design for a tray, dish, plate, platter, bowl, compote, basket, or analogous article of hollow ware, substantially as shown and described.

GEORGE F. PARKER.
